UNITED STATES PATENT OFFICE.

JOHN A. WESER, OF NEW YORK, N. Y.

VALVE FOR PNEUMATIC PIANO-PLAYERS, &c.

1,048,615.

Specification of Letters Patent.

Patented Dec. 31, 1912.

Application filed December 12, 1911. Serial No. 665,363.

To all whom it may concern:

Be it known that I, JOHN A. WESER, a citizen of the United States, residing in the borough of Manhattan of the city of New York, New York county, State of New York, have invented certain new and useful Improvements in Valves for Pneumatic Piano-Players, &c., of which the following is a specification, reference being had to the accompanying drawing, which forms a part hereof.

The invention relates to valves such as are commonly used in pneumatic playing devices for musical instruments and for other purposes, and has for its object to improve the construction and operation of such valves, to reduce the cost of manufacture and to enable them to be placed in position and adjusted readily.

20 The invention will be more fully explained hereinafter with reference to the accompanying drawing in which it is illustrated and in which the single figure is a detail view in section illustrating a valve structure such as is commonly employed in the pneumatics of pneumatic piano players, embodying the improved valve.

It will be obvious, as this description proceeds, that the improved valve may be employed in any valve structure in which it is possible to use a valve of similar type. For convenience in explanation of the nature of the invention, however, it is shown in the drawing as applied to an ordinary form of valve structure, commonly employed in the pneumatics of pneumatic controlling devices of piano players. This structure comprises, as shown, a valve casing *a*, having in its top an aperture in which is mounted 40 frictionally ring *b* with a central port *b'* and in the other side a valve cup or ring *c* with a central port *c'*, the port *b'* usually opening to atmosphere and the port *c'* to the vacuum system of the player, a diaphragm chamber *d* with its diaphragm *d'*, and a button *e*, provided with an adjusting screw *e'*, by which the movement of the diaphragm controls the valve which is placed within the valve chamber *a'*.

50 The valve *f* is suited in form to the particular use for which it is designed. In the form shown it comprises a central body *f'*, which may be of very light and soft felt or other suitable material, top and bottom caps *f²* and *f³* which are sufficiently large in diameter to cover the valve ports and may be

of felt somewhat stiffer than the body, or of other suitable material, and contact pieces *f⁴* and *f⁵* of thin leather, for contact with the valve cups or rings *b* and *c*. The contact piece or cover *f⁵*, adjacent to the diaphragm, is preferably imperforate, as shown, while the contact piece or cover *f⁴* on the opposite end of the valve, is perforate, as at *f⁶*, having an aperture of relatively small diameter to co-operate with the guide pin hereinafter referred to. The body of the valve, including the caps, is recessed as at *f⁷*, the recess having a diameter relatively greater than that of the guide pin. 70 The valve may therefore tilt with respect to the stationary guide pin and so adapt itself to the position of the valve ring *b* or *c* as the case may be. The valve is guided in its movements by a stationary guide pin *g* 75 which is suitably supported so as to enter the recess in the valve itself through one side. In the construction shown it enters freely through the aperture *f⁸* in the cover *f⁴*, which is nevertheless of such relatively 80 small diameter that the valve is maintained substantially in axial position in its movement. The stationary guide pin is not long enough to penetrate the valve completely in any position of the valve, the opposite end 85 of the recess *f⁷* being preferably closed by the imperforate cover *f⁵*, so that there is no leakage of air through the valve itself. The recess *f⁷* however, is sufficiently large to permit the valve to tilt with respect to the 90 guide pin and therefore to adapt itself to any relative position of the valve seat. The guide pin is preferably formed of a bent wire and secured in the valve ring *b*.

95 The wire *g*, which forms the guide pin, being bent in U shape, as shown, is readily secured in place by driving the short member into the valve ring *b* and does not project above the upper surface of the casing 100 nor require screws or cross-bars or other devices to hold it in place. Being secured to the valve ring before the latter is placed in position it is itself placed in position with the valve ring and requires no further manipulation. The upper valve ring *b*, as will 105 be observed, is larger in diameter than the valve *f* so that the latter can be dropped into place through the aperture in which the valve ring is subsequently placed. Furthermore, through the placing of the button *e* 110 on the diaphragm and the location of the adjusting screw *e'* in the top of the button

the necessary adjustment to regulate the lifting of the valve can be effected before the valve and the upper valve ring are put in place. And moreover, since the button is 5 fixed with respect to the diaphragm, usually being glued thereto and the point of contact between the button and the valve is in or above the plane of contact between the valve and the lower valve ring, the valve itself will 10 be moved more easily and more certainly into its desired position, since it bears directly with free rocking movement on the top of the button, than would be possible if the valve were provided with a stem extending 15 downward below the plane of contact between the lower valve ring and the valve to the surface of the diaphragm.

I claim as my invention:

1. In a valve structure of the character 20 described, the combination of a valve casing having opposite ports, a valve within the casing, said valve comprising an imperfo-

rate bottom, a recessed body and a perforate top, a stationary guide-pin entering the valve freely from above, a diaphragm to 25 control the valve, a button on the diaphragm, and an adjusting device supported by the button.

2. In a valve structure of the character described, the combination of a valve casing, 30 a valve ring inserted in one side of the casing and forming a valve seat, a valve therefor located in the casing, and a U-shaped wire having one member driven into the valve ring and having its other member extended centrally into the valve casing to 35 form a stationary guide-pin for the valve.

This specification signed and witnessed this 8th day of December A. D., 1911.

JOHN A. WESER.
